DESIGN FOR A COMBINED CUTTER AND EJECTOR FOR BISCUITS, COOKIES, OR THE LIKE

Frank A. Johnson, San Francisco, Calif.

Application March 22, 1943, Serial No. 109,787

Term of patent 14 years

(Cl. D44—29)

To all whom it may concern:

Be it known that I, Frank A. Johnson, a citizen of the United States of America, residing at San Francisco, in the county of San Francisco and State of California, have invented a new, original, and ornamental Design for a Combined Cutter and Ejector, for Biscuits, Cookies or the like, of which the following is a specification, reference being had to the accompanying drawing, forming a part thereof.

Fig. 1 is a front elevation of a combined cutter and ejector, for biscuits, cookies or the like, showing my new design; and

Fig. 2 is an edge elevation of the same.

I claim:

The ornamental design for a combined cutter and ejector for biscuits, cookies, or the like, as shown.

FRANK A. JOHNSON.
